UNITED STATES PATENT OFFICE

2,003,300

FIRE EXTINGUISHING DEVICE

Charles H. Meigs, New York, N. Y., assignor to
Du-Gas Fire Extinguisher Corporation, New
York, N. Y., a corporation of Delaware

Application April 11, 1932, Serial No. 604,406

1 Claim. (Cl. 169—36)

My invention relates to improvements in fire extinguishers of the type which comprises a non-refillable container filled with a powder which has fire extinguishing properties.

Previously, such extinguishers have been made by filling tube-like containers with a powder adapted to extinguish fires. These containers were provided with an opening at one end through which the powder could be thrown out onto the fire. When not in use, the opening was covered with a readily removable cap. This type of extinguisher has been unpopular, since it was useful only when the fire was sufficiently small so that the operator could approach relatively close, which was necessary in order to spread the material on the exact scene of the conflagration.

An object of this invention is to provide a fire extinguisher which may be thrown on a fire and thus be used effectively when the operator is at a considerable distance from the fire, or which may be used as a sprinkler to distribute the powder locally of the operator.

A further object of this invention is to provide a fire extinguishing material in a relatively cheap, non-refillable container so that an adequate supply may be placed at various points in buildings at a minimum expense.

A further object of this invention is to provide an extinguisher which will function automatically in case a fire starts when no person is around to operate an extinguisher.

A further object of this invention is to provide an extinguisher which will extinguish the fire with little or no damage other than that caused by the fire itself.

Other and further important objects of this invention will become apparent from the following description and appended claim.

Several forms of my invention are illustrated in the drawing and are hereinafter more fully described.

On the drawing:

Figures 1, 2, 3 and 4 each represent a different modification of my device, shown partially in elevation and partially in section.

The reference numerals 5, 6, 7 and 8 indicate possible forms of containers, preferably of glass, and hermetically sealed at suitable points as at 9, 10, 11 and 12. Each of these containers when intended for use as hand grenades to be thrown on a fire is filled with a fire extinguishing powder 13; but when the containers are intended for use automatically, they are only partially filled, leaving a sufficient space as at 21, 22, 23

and 24 to contain air or some other suitable gas preferably at or above the pressure of the atmosphere. Suitable levels for the powder in the various modifications of my device are indicated by the dotted lines 14, 15, 16 and 17. These levels are not critical but may be located at various points within the container. This fire extinguishing powder may be any composition adapted to the purpose. A suitable composition is disclosed in United States Patent No. 1,793,420. 10

Figure 1 shows the approximate form of my invention in which I prefer to make small sized extinguishers for hand use, holding one pound of powder, more or less. This is a very convenient shape and size for throwing at fires originating in automobiles, in electrical apparatus, or any other place where it is possible to throw the extinguisher directly into the fire.

Figure 2 illustrates a form which I prefer for larger capacity extinguishers for automatic use. 20 It may contain 25 pounds of powder, the exact amount not being essential to my invention, but in any event the powder need not fill the container, any required air or gas space being left. One or more of this type of extinguisher may be 25 placed in the top of an oil or gas tank, on a lacquering booth, or other place where a fire of large proportions could develop in an instant due to the presence of large quantities of highly inflammable material. Such fires frequently reach 30 unmanageable proportions almost at the instant of ignition so that the use of hand extinguishers is not only ineffective but unsafe for the operator. However, a sufficient number of my extinguishers may be placed over the inflammable 35 material to protect its entire surface. The heat of the fire will expand the air or gas in the space 22 above the surface of the powder, causing the bulb to burst, scattering the powder over the fire. The heat will also liberate gases from the fire extinguishing powder, which may also assist in creating the pressure necessary to burst the container 6.

Figure 3 shows an extinguisher which works in a manner analogous to the one illustrated in 45 Figure 2, but I prefer this shape for a smaller extinguisher containing from 2 to 10 pounds more or less of powder, not sufficient to fill the container, leaving suitable air or gas space. I prefer this size to suspend in places in or about buildings 50 where fire hazards exist. When the fire starts, the heat causes the gases within the extinguisher to expand and burst the container, as explained above, scattering the powder about and extinguishing the fire.

I may also suspend the extinguisher on an inflammable or fusible link, which will burn or melt from the heat of the fire, allowing the extinguisher to drop, but this is unnecessary since the extinguisher will burst from the heat, whether it is allowed to drop or not.

Figure 4 is a modification of my invention which is provided with a portion 18, which may be broken off from the body of the container by striking it against any suitable surface. The container 8 is so designed that the portion 18 will break off along the line 19, or as may otherwise be desired. This can be accomplished by means of a groove or scratch along the line 19, or by making the glass very thin in this portion of the container 8. Any modification of the glass at the line 19 which will favor a clean break without shattering the body of the container 8 will be operative in my invention. The purpose of the restricted portion 20, of the container 8 is to facilitate a firm hand-grip of the said container by the operator. It also assures that the tube will be held in a manner that will be best adapted to empty said container without losing powder on the back stroke. It also causes the powder to flow from the tube at a uniform rate.

This modification of my device is designed especially for fighting small fires at close range. It is grasped by the hand and struck against any convenient surface to break off the portion 18 along the scratch or groove 19, leaving an opening through which powder may be poured onto the fire. This type is especially desirable to carry in automobiles and, like the other styles described above, will explode if a fire should start when no one is around, causing the powder to be scattered about, extinguishing the fire, although when this automatic action is desired, it is preferable to have the container only partially filled with the powder, leaving suitable space for air or gas.

For some purposes, it is an advantage to have air or gas in the space above the powder in my various extinguishers somewhat above atmospheric pressure to cause the explosion of the ex-

tinguisher to take place before the fire has reached the proportions necessary to cause an explosion when the air in the container is only at atmospheric pressure.

I prefer that the container be transparent, since this feature makes the device more attractive to the purchaser, who is able to see clearly the principle involved. However, it will be understood that colored or opaque glasses and various other opaque material may be used, as well as numerous other transparent materials, such as celluloid, cellophane, gelatine, etc. In each case, it is only necessary that the container be sufficiently weak or friable to burst under the pressure which will be developed when the air or gas within the container is heated by the fire.

It is preferable that the container be made of a fragile material such as glass, since a glass container will shatter in breaking allowing the powder to be scattered uniformly in various directions. A container of tin, for example, would be apt to break in but one place leaving a large portion of its surface intact. This intact portion would then act as a shield to prevent the uniform scattering of the powder over the fire. By the use of a container of fairly thin glass, I am able to overcome this difficulty.

It will be understood that the term "hermetically sealed" as used in the following claim means sealing by fusion and does not include other sealing means.

I am aware that numerous details of my invention may be varied through a wide range without departing from the spirit of my invention, and I, therefore, do not desire to limit the patent granted hereon other than as necessitated by the prior art.

I claim as my invention:

A fire extinguisher comprising a fragile, one-piece, hermetically-sealed glass container containing powder adapted to extinguish fires, and a gas under pressure.

CHARLES H. MEIGS.
